UNITED STATES PATENT OFFICE

153,882

DESIGN FOR A BOTTLE CARRIER

Joseph K. Laier, Kansas City, Mo.

Application February 9, 1948, Serial No. 144,371

Term of patent 7 years

(Cl. D58—4)

To all whom it may concern:

Be it known that I, Joseph K. Laier, a citizen of the United States, residing at Kansas City, in the county of Jackson and State of Missouri, have invented a new, original, and ornamental Design for a Bottle Carrier, of which the following is a specification, reference being had to the accompanying drawing, forming a part thereof.

Fig. 1 is a top plan view of a bottle carrier, showing my new design.

Fig. 2 is a side elevational view thereof; and

Fig. 3 is an end elevational view thereof.

I claim:

The ornamental design for a bottle carrier, as shown.

JOSEPH K. LAIER.
